UNITED STATES PATENT OFFICE.

ALBERT LATHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,187,071.

Specification of Letters Patent. Patented June 13, 1916.

Original application filed December 26, 1912, Serial No. 738,647. Divided and this application filed May 23, 1913. Serial No. 769,366.

To all whom it may concern:

Be it known that I, ALBERT LATHAM, a citizen of the United States, residing at Beverly, in the county of Essex and State of Massachusetts, have invented certain new and useful Improvements in Sewing-Machines; and I do hereby declare the following to be a full, clear, and exact description of the invention, such as will enable others skilled in the art to which it appertains to make and use the same.

The invention relates to shoe sewing machines and more particularly to thread severing and holding devices for such machines.

15 This application is a division of application 738,647, filed December 26, 1912.

20 The object of the invention is to provide novel thread severing and holding devices which are well adapted for use in welt and turn shoe sewing machines, and which will hold the severed end of the thread under tension during the formation of the initial stitches of the seam without danger of breaking the thread.

25 To this end the invention consists in features of construction and combinations of parts hereinafter described and referred to in the claims.

30 The invention will be readily understood from an inspection of the accompanying drawings and the following detailed description of the mechanism illustrated therein.

35 In the drawings Figure 1 is a side elevation showing so much of a welt and turn sewing machine as is necessary to illustrate the application of the present invention thereto. Fig. 2 is a detailed plan view of the thread holding and severing devices and Fig. 3 is a detailed side elevation with 40 thread holding clip and cutter plate.

45 The machine shown in the drawings is a machine for sewing welt or turn shoes, and is provided with a curved hook needle 1, the looper 2, the thread finger 3, the back gage 4 and the channel guide 5, all of which are operated in the usual manner from the cam shaft of the machine. The machine is also provided with devices by which the thread may be conveniently severed at the completion 50 of the sewing and held in proper position for the beginning of the next succeeding sewing operation. In the construction shown, the devices, for severing the thread and holding the severed end of the thread

supply, consist of a thread holder in the 55 form of a spring finger 6 formed on a plate 7 adjustably secured to an arm 8. The spring finger is arranged to coöperate with the upper corrugated surface of the arm in firmly gripping the thread introduced between the finger and arm. A cutter plate 9 is secured to the side of the arm 8 in position to sever the thread when it is drawn under the finger 6 as indicated in Fig. 2. The arm 8 is adjustably secured in a socket 60 formed in the end of an arm 10 which is pivoted at 11 on the frame of the machine and is held in normal position by a spring 12. The retracted position of the thread holding arm is determined by a stop screw 70 13 and the forward movement of the arm is determined by a stop screw 14.

75 After the machine has been brought to rest at the completion of the sewing of the shoe, and after the welt has been severed, in case the machine is operating upon welt shoes, the operator raises the shoe and draws the thread leading from the shoe to the looper under the spring finger 6, thus introducing the thread into the holder and severing the thread from the thread supply. At the beginning of the next succeeding sewing operation the end of the thread beyond the thread handling devices is held by the thread 80 holder and forward movement of the thread 85 is resisted by the spring 12. The thread is, therefore, held under tension while the arm 10 may swing forward toward the sewing point against the tension of the spring 12 to give up thread to the thread handling devices during the formation of the first stitch or stitches. The formation of a tight seam at the beginning of the sewing operation is thus insured, while breaking of the thread under sudden strains or pulls exerted by the 95 thread handling devices is avoided by the yielding of the spring 12. The thread holder continues to hold the thread under tension during the continuation of the sewing until the forward feed of the shoe draws the 100 thread from the thread holding finger.

105 While it is preferred to employ the specific construction and arrangement of parts shown and described, it should be understood that this construction and arrangement is not essential to the broader features of the invention and may be varied or modified without departing therefrom.

Having explained the nature and object of the invention, and specifically described one form of mechanism in which it may be embodied what I claim is:—

5. 1. A sewing machine, having, in combination, stitch forming devices, a thread holder for holding the free end of the thread constructed and arranged to be moved toward the sewing point by a pull on the thread, 10 and a spring arranged to resist said movement and constructed to yield under the pull of the stitch forming devices.
15. 2. A sewing machine, having, in combination, stitch forming devices, an arm mounted for movement toward the sewing point to give up thread to the stitch forming devices, a spring arranged to hold the arm in retracted position and constructed to yield under the pull of the stitch forming devices, 20 and a holding device on the arm constructed to retain the free end of the thread until it is withdrawn by the feed of the work.
25. 3. A sewing machine, having, in combination, stitch forming devices, an arm mounted for movement toward the sewing point to give up thread to the stitch forming devices, a spring arranged to hold the arm in retracted position and constructed to yield 30 under the pull of the stitch forming devices, and a spring finger on the arm for frictionally holding the thread.
35. 4. A sewing machine, having, in combina-

tion, stitch forming devices, and a device for holding the end of the thread constructed 35 to yield under the pull of the stitch forming devices during their initial cycle.

5. A sewing machine, having, in combination, stitch forming devices, a thread holding clamp mounted for movement toward 40 the sewing point to give up thread to the stitch forming devices, and a spring arranged to hold the clamp in normal position and constructed to yield under the pull of the stitch forming devices. 45

6. A sewing machine, having, in combination, stitch forming devices, a thread holding clamp constructed to yield under the pull of the stitch forming devices during their initial cycle, and a thread severing 50 blade at one side of the clamp.

7. A sewing machine, having, in combination, stitch forming devices, a thread severing device for severing the thread at the completion of the sewing operation, a pivoted thread holder for holding the end of the thread, and a spring arranged to hold the thread holder in normal position and constructed to yieldingly resist its movement under the pull of the stitch forming 55 devices. 60

ALBERT LATHAM.
